UNITED STATES PATENT OFFICE.

ALBERT M. FULLER, OF PITTSBURGH, PENNSYLVANIA.

SAFETY RAZOR.

Application filed September 20, 1920. Serial No. 411,518.

To all whom it may concern:

Be it known that I, ALBERT M. FULLER, a citizen of the United States, and a resident of Pittsburgh, in the county of Allegheny and State of Pennsylvania, have invented a new and useful Improvement in Safety Razors, of which the following is a specification.

This invention relates to safety razors.

10 Among the objects of the invention are the provision of a safety razor having only two essential parts, namely, a blade support and a blade; a blade for such a razor in the form of a thin flat, non-flexible member; means 15 for engaging the blade and its supporting member consisting of one or more tongues and cooperating openings, the tongues being on the blade and the openings on the other member; and in general the making of a 20 safety razor reduced to its simplest form in all respects.

The construction hereinafter set forth permits the blade support and its handle to be developed from one piece of stamped 25 sheet metal, thereby eliminating the necessity of any forging, machining, or other expensive operations thereon, and so greatly reducing the cost of manufacture. The construction also provides a safety razor, the 30 blade of which may be made in a standardized form and interchangeably used with different forms of supports. These and other objects which will be apparent to those familiar with the art will more fully appear 35 in the following specification.

Referring to the drawings, Fig. 1 shows a "hoe-shaped" blade support forming one of the two essential parts of the complete razor constructed according to this invention, the view being an elevation of the handle, standing on end; Fig. 2 is a view similar to Fig. 1 but taken at right angles thereto and with the razor blade in position on the handle; Fig. 3 shows another form 45 of holder and handle the two portions being in alignment; Fig. 4 is a section on the line IV—IV of Fig. 3; Fig. 5 is a perspective view of a preferred form of blade, suitable for use with any of the supports illustrated; Fig. 6 shows a special blade holder applied to the ordinary form of razor handle; Fig. 7 is an enlarged partial section 50 through the blade and its support, the blade having been applied to the support, but not 55 having been moved longitudinally into permanent engagement therewith; and Fig. 8

is a section through the blade and its support showing the relative position after the blade has been longitudinally moved into engagement with the support. The last two 60 figures also show a modification in the end of the blade.

Safety razors have been made heretofore, in which a blade of substantial thickness having a pair of slots, each slot having a 65 countersunk ledge adjacent thereto, has been combined with a support, the support having a shank pivoted thereto and being provided with an integral guard having a pair of integral lugs off-set from said guard and 70 adapted to pass through the slots and engage the ledges of the blade, to hold the blade and guard together. Likewise thin flexible wafer steel blades have been provided for attachment to a support by means 75 of projecting overhanging lugs on the support adapted to extend through holes in the blade, and to engage the blade, holding it in a curved position against the handle by means of the resiliency of the blade itself, 80 and without any additional locking member.

The present invention is distinguished from each of these by the fact, among others, that it does not use a wafer blade, and the 85 blade itself is of uniform thickness throughout its body and is not bent or distorted in any way either while held in operative position or in order to place it in operative position. Furthermore the blade of the present device is not held in position by a third part, clamping the blade between such third part and the handle as has heretofore been the practice wherever a stiff blade was used. 90

The present invention in all of its forms 95 provides for holding the blade and its support together by means of one or more off-set tongues formed integrally with the blade, which tongues engage the holder and by their resiliency hold the two securely together under pressure.

Referring to the drawings the support or holder for the blade used with this invention may be made from a piece of sheet metal rolled up to form a round handle H shown 105 in Figs. 1, 2 and 3. Figs. 1 and 2 show the so-called "hoe-pattern" razor, while Fig. 3 shows a straight construction. In Fig. 6 is shown a metal member 1, adapted to take the place of the ordinary blade in the old fashioned razor handle 2. It will be observed that the handles H and H² are made 110

by rolling up a strip of sheet metal to form a suitable hand-hold at one end, the other end being fashioned into a supporting plate S adapted to hold the blade as below described. For example in Fig. 1 the same piece of metal sheet which forms the handle H forms the blade support S. The outer edge of the supporting portion S has a series of openings O therein, which are separated by small grill-like portions of metal G forming a guard portion which readily slides over the face of a person shaving, and permits the blade B, shown in Fig. 2 to come in contact with the beard. The portion of support S which is cut away to form the guard portion is turned slightly inward as shown in Fig. 2 and the outer edge is turned sharply inward, forming a bounding flange F as shown. The flattened plate-like portion adapted to hold the blade is marked with the reference letter S in each figure; the blade with the letter B, the handle H, etc.

In Figs. 1 and 2 this supporting portion S has cut through it two sets of openings C and C'.

In the form shown in Fig. 3 the sheet metal that forms the handle H³ likewise forms a blade holding portion S³ and at each edge of this flat portion the metal is cut away to form a series of openings O³, with intervening guard portions of metal G³. The outer edge is turned sharply inward, forming a terminal flange F³. The section shown in Fig. 4 clearly shows the construction just above referred to. The supporting portion S³ has a pair of openings C³, intermediate which there is a small rounded hump P³.

The form of handle shown in Fig. 6 comprises the metal bar 1, which is pivotally attached to an ordinary razor handle 2 by a rivet 7. This rivet passes through the forked end of the handle 2, the slot 8 forming this forked portion being extended far enough into the handle so that the tang 9 of the member 1 can pass through the slot, thus permitting the razor to be used for shaving with either hand or with either edge of the blade as will be obvious.

This member 1 likewise has a flattened blade supporting portion S⁶ similar to portions S and S³ above described, and this flat portion has a pair of openings C⁶ therethrough, with an intermediate raised hump P⁶, as illustrated. The edges of the supporting member S⁶ are serrated, forming guard teeth G⁶; and these serrations are similar on each side of the member, as illustrated.

The preferred form of blade is shown in Fig. 5. It consists of a piece of thin flat steel B having two cutting edges E, and two raised integral tongues T, which are struck up from the body of the blade B and having re-entrant bends 10, and outwardly turned terminal portions 11, as more clearly

shown in Figs. 7 and 8. Intermediate the tongues T is a small round hole 12 punched through the blade, and near it and aligned with it and the tongues is an elongated perforation 13.

This blade is adapted to be used with each of the three forms of holders illustrated respectively in Figs. 1 and 2, Fig. 3, and Fig. 6.

The blade B is fastened to its support by laying it flat upon the supporting surface S, the tongues T being positioned in the openings C, and occupying the position shown in Fig. 7. It will be observed that the raised hump P, when the blade is laid upon the flat supporting surface S, lies in the elongated opening 13 of the blade. With the blade in this position, it is pushed longitudinally on its supporting surface. The terminals 11 of the tongues T pass outside of the undersurface of the supporting plate S, and further movement causes them to ride upon the underside of said supporting member and to engage that member, as shown in Fig. 8. The movement to this position necessitates a springing outward of the tongues T, and consequently results in a resilient locking action of such tongues upon the supporting member S. At the same time, the middle portion of the blade rides up over the hump P, until that member registers with the round opening 12 in the blade, as illustrated in Fig. 8, which acts as a lock for holding the blade firmly in place upon its support. This hump P and cooperating hole 12 are not absolutely necessary, since the blade will ordinarily be held with sufficient certainty by the resilient force of the tongues T.

It will be observed that the blade illustrated in Fig. 5 may be interchangeably used with any of the forms of support and the different handles shown. With the supports shown in Figs. 3 and 6 the blade is held in position so that either side may be used for shaving without change. With the support of Figs. 1 and 2 however only one cutting edge is in position for use, and in order to use the other edge, the blade is taken off, turned end for end, and then engages the other pair of holes C or C', as the case may be, of the support shown in Fig. 1.

The blade may be provided with a down-turned flange 15, at one end which makes it easier to slide it into place by pressure with the fingers. This construction is shown in Figs. 7 and 8.

It will be apparent that many modifications may be made in varying the attaching elements. No attempt has been made to illustrate all of them. Instead of holes, loops of metal may be used to engage the tongues, and other equivalents. These are understood to be within the scope of the appended claims.

I claim:

1. A safety razor comprising a blade

holder having openings therein, and a self-fastening blade having cooperating, integral, resilient, offset tongues struck up from the body of the blade, said tongues being 5 adapted to pass through the openings in the holder and ride over and engage the edges thereof upon relative movement of the blade and the holder, whereby to clamp the blade to the holder by pressure of the tongues and 10 blade body on opposite sides thereof.

2. In a safety razor, the combination with a holder of a self-fastening blade having longitudinally extending, integral, resilient offset tongues struck up from the body of the 15 blade, the holder having cooperating openings adapted to receive said tongues, the tongues being adapted to ride over and engage the edges of the holder adjacent to the opening when the blade is moved longitudinally relative to the holder.

3. A safety razor blade of uniform thickness throughout its body, having integral resilient tongues struck up from the blade 20

body, said tongues being bent first away from the body and then into substantially 2 parallel position relative to the body, whereby the tongues are adapted to ride over and engage the edges of a supporting member between the tongue and body of the blade upon movement of the blade in the direction 30 of the free ends of said tongue.

4. A safety razor comprising a blade support having openings therein, and a thin light blade of uniform thickness throughout and having integral, resilient offset tongues 35 struck up from the blade and adapted to pass through the said openings and to clamp the edges of the holder between the said tongues and the blade body upon relative longitudinal movement of the blade and 40 support.

In testimony whereof, I have hereunto set my hand.

ALBERT M. FULLER.

Witness:

HOWARD L. SNIVELY.
